UNITED STATES PATENT OFFICE.

JOHN C. NORRIS, OF DENVER, COLORADO.

LAMP SHADE OR REFLECTOR.

No. 901,641.

Specification of Letters Patent.

Patented Oct. 20, 1908.

Application filed April 29, 1907. Serial No. 370,919.

To all whom it may concern:

Be it known that I, JOHN C. NORRIS, a citizen of the United States, residing in the city and county of Denver and State of Colorado, have invented certain new and useful Improvements in Lamp Shades or Reflectors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in shades or reflectors for lamps and while more especially adapted for use in connection with electric lamps, its use of course is not limited thereto but it may be employed 20 wherever a device of this general character is required.

My improved lamp shade or reflector consists of a device having a perforated central portion from which extend a number of 25 radially disposed parts consisting of two sets occupying different inclined planes, the upper and lower parts alternating with each other and forming partial sectors of a circle, the central portions of the sectors, however, 30 being interrupted by the central perforation. The lower sides of these radially disposed parts are provided with reflecting surfaces. The two sets of parts are connected by 35 radially disposed parts forming angles with the first named parts. As shown in the drawing these connecting parts form right angles with the two sets of connected parts. The exact angle of the said connecting parts, however, is not essential and may be varied. 40 These connecting parts are formed of transparent material, whereby a portion of the light from the lamp or other illuminating device is allowed to pass through, thus giving a considerable degree of illumination 45 above the shade or reflector, thereby distinguishing my improved construction from a perfect reflector or a device which reflects all of the illuminating rays.

Having briefly outlined my improved construction, I will proceed to describe the same in detail reference being made to the accompanying drawing in which is illustrated an embodiment thereof.

In this drawing, Figure 1 is a top plan view of my improved device. Fig. 2 is a perspective side view of the same. Fig. 3 is a sectional detail view.

The same reference characters indicate the same parts in all the views.

Let the numeral 5 designate the central portion of my improved device having the perforation 6. From the part 5 lead two sets of radially disposed parts designated 7 and 8, respectively. These parts 7 and 8 are alternately arranged, the parts 7 being 65 at a greater elevation than the parts 8. These two sets of parts are connected by triangular parts 9 forming suitable angles with the parts 7 and 8. These parts 9 are also radially disposed and as shown in the drawing form right angles with the parts 7 and 8. The parts 7 and 8 if formed of glass or other transparent material, are coated on their upper surfaces whereby their lower surfaces constitute reflectors. This coating 75 is designated Q in Fig. 3. This figure also shows that the angle parts 9 are transparent and non-reflecting, whereby the light from the illuminating device is allowed to pass freely therethrough, thus giving a considerable 80 degree of illumination to surrounding objects as heretofore explained.

Having thus described my invention, what I claim is:

1. A lamp shade or reflector comprising a 85 central perforated portion from which lead radially disposed parts arranged at different elevations, and parts arranged at suitable angles and connecting the radially disposed parts, the said connecting parts being transparent 90 while the lower surfaces of the connected parts constitute reflectors, substantially as described.

2. In an improved article of manufacture, 95 a shade or reflector having a central portion from which lead two sets of radially disposed inclined segmental sectors arranged at different elevations, and transparent parts arranged at suitable angles and connecting the two sets of sectors, the two sets of connected parts forming reflectors, for the purpose set forth.

3. A lamp shade or reflector comprising a central portion from which lead two sets of radially disposed inclined parts arranged at 105 different elevations and alternating with each

other, and transparent parts arranged at suitable angles and connecting the two sets of parts, for the purpose set forth.

4. A lamp shade or reflector comprising a central portion from which lead two sets of radially disposed inclined parts arranged at different elevations and alternating with each other, the lower surface of the said parts forming reflectors, and means for connecting

the two sets of parts to permit the light 10 from the illuminating device to pass freely between said parts, for the purpose set forth.

In testimony whereof I affix my signature in presence of two witnesses.

JOHN C. NORRIS.

Witnesses:

DENA NELSON,
MAY GAWLEY.
